PUMP.

1,299,157.

Specification of Letters Patent.

Patented Apr. 1, 1919.

Application filed May 1, 1917. Serial No. 165,688.

To all whom it may concern:

Be it known that I, FRANK A. FAY, a citizen of the United States, residing at Caldwell, in the county of Essex and State of New Jersey, have invented new and useful Improvements in Pumps, of which the following is a specification.

My invention relates to pumps, particularly those adapted for deep wells, and consists in a new construction and arrangement of parts whereby the crystallizing and breaking of the gears due to irregular shocks are overcome. In these pumps as now commonly made, when the crank goes by the center on the up stroke, the weight of the column of water, rods, valves, etc., drops with a sudden shock whereby the teeth are worn, (or broken) which causes hammering and back lash, resulting in crystallization and final breaking of the teeth. This defect and danger has long been recognized and attempts have been made to overcome it, for instance by making the rods out of wood or piping to lighten the weight and reduce the shock.

Such attempts are merely palliatives but I have overcome the trouble by introducing at some suitable point a cushion, or frictional resistance, to prevent sudden drop of the rod, etc., and to prevent shock on the gears,

My invention is illustrated in the drawing herewith, in which the invention is shown embodied in a suitable concrete form and wherein the reference characters of this description are applied to corresponding parts in the several views.

In the drawing Figure 1 is a vertical sectional view of a pump embodying the features of my invention; Fig. 2 is a view in side elevation at right angles thereto; and Fig. 3 is a detail vertical sectional view of the fluid check device thereof.

In the construction shown the operating parts of the pump are supported in a suitable standard 1 and consist of the driving pulley 2 journaled on a shaft 3 having drive pinion 4 thereon in mesh with the crank-gear 5 having eccentric pin 6 to which is connected the connecting rod 7 connected at its upper end to stud 8 of a vertically reciprocating slide 9 operating on a suitable way 10 on the standard. Also connected to the stud 8 is the vertically operating piston rod 12 of the pump which carries the usual piston, not shown, operating within the cylindrical well

pipe 13 suspended from the supporting cap on member 18 whose flanged upper end rests upon the base portion of the standard. In so far as described the arrangement is of the usual construction.

In accordance with my invention a fluid compression device is arranged to be associated with the reciprocating parts as described in a manner whereby it will act thereon to cushion or check the descent of the parts upon the crank-pin passing center after completing the up stroke and is so located, below the standard, as to avoid freezing. In the approved arrangement of my invention here shown the cushion device comprises a check piston element 14 affixed to the pump rod 12 and operating within a cylindrical chamber 15 formed in the cylindrical member 16 which, within the well pipe, is threaded at its upper end to the supporting member 18 and is closed at its lower end by the cap element 17 threaded thereto, the cap member being provided with a central bearing through which the piston rod passes.

A valve disk 21 is arranged as shown yieldingly supported against the piston by means of a light coil spring 22 bearing upon a shoulder 23 of the piston rod. The piston is provided with openings 24 and the valve disk is formed with small perforations 25 as indicated to restrict the passage of fluid therethrough. The frame 15 is filled with a suitable fluid, for instance water from the rising column of water in the well pipe 90 which will enter the chamber through openings 23 provided therfor in the casing 16.

In operation the valve disk 21 will yield against the influence of the spring 22 on the upstroke of the piston rod but on the return down stroke will be forced against the piston 15 by the pressure of the fluid and will frictionally retard the down stroke proportionate to the resistance resulting from the restricted area of the small openings 25 therein. The arrangement thus provided will operate to support the parts during the downward return stroke of the piston and thereby relieve the parts from shock, while the chamber itself, which is located within the well pipe, is surrounded by the column of rising water therein as it passes to the usual discharge opening 32.

As here shown the cushioning chamber, which is dropped below the surface only a

short distance but sufficient to illustrate the intention, extends downwardly into a sump-pit 30 from which extends downwardly the main well pipe, but if desired the chamber 5 might be arranged extending downwardly from the bottom of the sump-pit, and would be normally warmed by the pumped liquid, or otherwise, and kept at a substantially constant temperature, so that the compression 10 chamber arranged therein would be protected from freezing, and, if extending below, would be remote from frost.

Having described my invention, I claim,
15 In a pump having a reciprocating piston,
a well pipe, a piston rod operating therein,
operating means for the piston rod, and a
cushioning means adapted to cushion the re-

turn stroke of the parts comprising a cylindrical fluid check, a casing supported within the well pipe, a buffer piston affixed to the 20 piston rod and operating within the cylindrical casing, a yielding valve coacting with the buffer piston and adapted to permit comparatively free passage of the fluid on the lift stroke of the piston rod and to restrict 25 the passage of the fluid on the return stroke, said buffer piston being arranged to operate below the outlet passage of the well pipe and openings from the well pipe into the 30 casing substantially as described.

In testimony whereof I have signed my name to this specification.

FRANK A. FAY.
